UNITED STATES PATENT OFFICE.

EDWARD J. STEARNS, OF EASTON, ASSIGNOR OF ONE-HALF TO GEORGE H. ROGERS, OF BALTIMORE, MARYLAND.

SASH-FASTENER.

SPECIFICATION forming part of Letters Patent No. 238,727, dated March 8, 1881.

Application filed December 16, 1880. (Model.)

To all whom it may concern:

Be it known that I, EDWARD J. STEARNS, of Easton, in the county of Talbot and State of Maryland, have invented certain Improvements in Sash-Locks, of which the following is a specification; and I do hereby declare that in the same is contained a full, clear, and exact description of my said invention, reference being had to the accompanying drawings, and to the letters of reference marked thereon.

This invention relates to certain improvements in that class of sash-locks in which an eccentric is secured by means of a screw to the sash, with its edge in contact with the sash-bead; and it consists in combining with an eccentric, placed as described, and the sash-bead, a tapered strip, which is located between the said parts, with its smaller end toward the upper part of the window.

In the further description of my said invention which follows, reference is made to the accompanying drawings, forming a part hereof, and in which—

Figure I is a front view of a window frame and sash provided with my improved lock. Figs. II, III, and IV are details of the invention on an enlarged scale.

Similar letters of reference indicate similar parts in all the views.

A is the window-frame, and B the sash. C is the sash-bead, and D the tapered strip, secured to the bead C in any suitable manner. E is an eccentric, fastened to near the bottom of the sash B by means of a screw, a. The eccentric has a circular slot, b, concentric with the hole c, which, in connection with a stop, d, allows of a limited circular movement of the device. The eccentric has a finger-piece, e, whereby it may be turned so as to clear the tapered strip D, as will be readily understood.

The finger-piece is also used as a weight to influence the full part of the eccentric toward the tapered strip. The tapered strip extends downwardly to a point where it will come in contact with the periphery of the eccentric when the window-sash is down, as shown in Fig. II, and a lock is thereby formed which prevents the opening of the sash, except by first turning the eccentric in the direction indicated by the arrow.

The object in tapering the strip D is to increase the friction between the said strip and the eccentric independently of that produced by the turning of the said eccentric as the window-sash is lowered, and the efficiency of the device is thereby greatly increased. It is obvious that the same effect is produced by having a tapered sash-bead faced with a strip of metal of uniform thickness, or a tapered bead without a facing-strip; but the tapered strip is preferred, as it may be sold with the eccentric to form a complete lock, and can be applied to any sash-bead now in use.

I am aware that it is not new to use an eccentric secured to a window-sash as a lock, and also that a strip having an inclined surface has been used as an element in sash-locks; but I am not aware that the two devices have been combined in the manner and for the purpose hereinbefore described.

I therefore claim as my invention—

A sash-lock consisting of the eccentric E and tapered strip D, when combined and applied to a window-sash and a frame substantially as herein specified.

EDWARD J. STEARNS.
